[57] **ABSTRACT**

Four hammers are spaced 90° apart about an axis along which a workpiece is movable. The hammers extend radially to the axis and are intended to carry at their free ends respective tools. Each of the tools comprises a block having the general shape of a quadrangular prism which has four longitudinal side faces. The block has a central web, which forms a narrow section of one of the longitudinal side faces and extends from one end of the block approximately over one half of the length thereof. The one longitudinal side face has a working face section which is wider than the narrow section and extends from the latter to the opposite end of the block and slopes symmetrically to the two longitudinal side faces which are adjacent to the one longitudinal side face. The web has two side faces, each of which has in a view on the one longitudinal side face a contour which corresponds to one-half of the contour of the working face section in a view on the other end of said block.

TOOL FOR USE IN A SWAGING MACHINE

This invention relates to a tool for swaging machines which comprise four hammers, which are spaced 90° apart and extend radially to the axis of the workpiece and at their ends carry respective tools and are adjustable to different depths of penetration and preferably blow at the same time.

The use of such swaging machines enables a manufacture of workpieces which are circular, square or rectangular in cross-section. The cross-sectional shape of the workpiece will be determined in that the hammers are set to a selected radial distance from the axis of the workpiece and the workpiece is caused to rotate or held against rotation on its axis. The workpiece will be swaged to a square cross-section if all four hammers are set to the same radial distance from the axis of the workpiece and said distance is equal to one-half of the side length of the desired square, and the workpiece does not rotate on its axis. If the hammers have the same setting and the workpiece is caused to rotate, a circular cross-section will be obtained. To form a swaged workpiece which is rectangular in cross-section, the hammers are set to the desired side lengths of the rectangular cross-section and the workpiece is not rotated. It was previously necessary to use different tools on the hammers for the three different modes of operation of the machine so that an exchange of tools was required for a change from the manufacture of swaged workpieces having a square cross-section to the manufacture of swaged workpieces having a rectangular or circular cross-section.

It is an object of the invention to provide for such swaging machines a tool which is equally suitable for the manufacture of swaged workpieces which are circular, square or rectangular in cross-section so that the tool is universal in its application and all four hammers always carry the same tools.

This object is accomplished by the invention in that the tool consists of a block, which has generally the shape of a quadrangular prism and is formed with two lateral recesses, which extend in the direction of the axis of the workpiece approximately over one-half of the length of the block and are open toward the workpiece and define a central web, the working face of the block slopes symmetrically towards the side faces of the block, which are transverse to the axis of the workpiece, and the side faces of the web conform to said sloping configuration of the working face. On that side which faces the workpiece, the block has the full width only in approximately one-half of its length and in the remaining portion of its length is formed only by the central web. This design has the advantage that entirely equal tools are provided on two adjacent hammers, which are offset 90°, and said tools are arranged so that their central webs extend opposite to that of the first-mentioned tool and their full-width sections can enter the lateral recesses of the intervening tool considered first. As a result, all four tools may be caused to nest so that only a square passage remains between them and the side length of the square cross-section of said passage depends on the width of the web. Hence, all four tools may blow at the same time without causing the tools to collide and only a passage having a small square cross-section is left between the hammers and corresponds to the smallest cross-section to be swaged. Adjacent tools may be turned through 180° because the working face slopes symmetrically toward the two sides of the block and the side faces of the web have a corresponding concave shape. The distance between the working faces of the tools is determined by the setting of the hammers and may be selected so that a swaged workpiece having a square or rectangular or circular cross-section is obtained. A square or circular cross-section will be obtained if the distances between the working faces of pairs of opposite tools are the same and the workpiece is moved through between the tools and is rotated about its axis or held against rotation about its axis, respectively. A swaged workpiece which is rectangular in cross-section will be obtained if the distances between the working faces of pairs of respective opposite tools are different and correspond to the lengths of the sides of the rectangular cross-section. The cross-sectional dimensions of the workpiece may be varied between limits which are determined by the entire width of the block

and the width of the web so that the same tools may be used to manufacture swaged workpieces having square or circular or rectangular cross-sections of different dimensions. In each hammer blow, the workpiece is always engaged and deformed on all four sides at the same time so that it will not be spread in one direction or the other.

In a development of the invention, the working face comprises a flat central portion, which is parallel to the base of the block, two tangentially adjoining, slightly curved transitional portions and two more steeply inclined, plane end portions, so that the working face has a shape which is suitable for a thorough swaging of the workpiece, inclusive of its core.

An embodiment of the invention is shown by way of example on the accompanying drawing, in which

FIG. 1 is a perspective view showing four tools which belong to one and the same machine and are in open position and

FIGS. 2 to 4 are, respectively, a front elevation, top plan view and side elevation showing an individual tool.

Each tool consists of a substantially prismatic block 1, which has a rectangular base 2. The longer side of the rectangular base extends in the direction of the axis 3 of the workpiece. The block 1 is formed with two lateral recesses 4, which extend approximately over one-half of the length of the block and define a central web 5. The working face 6 comprises a plane central portion *a*, which is parallel to the base of the block, two tangentially adjoining, slightly curved transitional portions *b*, and two more highly inclined, plane end portions *c* so that the working face slopes symmetrically to the side faces 7 of the block, which are transverse to the axis of the workpiece. The side faces 8 of the web are similarly shaped so that each side face 8 of the web conforms in shape to one-half of the working face.

FIG. 1 shows the relation of the four tools which are used in one and the same machine and secured to respective hammers. These tools are not only angularly spaced 90° apart but have different orientations so that the central webs 5 of adjacent tools extend in opposite directions. Owing to this arrangement, the tools can be caused to approach each other to such an extent that those block portions which have the full width of the block are received by the lateral recesses 4 of the adjacent tools, as is indicated in dash-and-dot lines in FIGS. 2 and 4. In the position corresponding to the closest approach of the tools to each other, the tools define between them a passage which has in cross-section the form of a square having a side length which is determined by the width of the web.

What is claimed is:

1. A tool for use in a swaging machine which comprises four hammers, which are spaced 90° apart about an axis along which a workpiece is movable and which hammers extend radially to said axis and are intended to carry at their free ends respective ones of said tools,

said tool comprising a block having the general shape of a quadrangular prism which has four longitudinal side faces,

said block having a central web, which forms a narrow section of one of said longitudinal side faces and extends from one end of said block approximately over one half of the length thereof,

55 said one longitudinal side face having a working face section which is wider than said narrow section and extends from the latter to the opposite end of said block and slopes symmetrically to the two longitudinal side faces which are adjacent to said one longitudinal side face, and

60 said web having two side faces, each of which has in a view on said one longitudinal side face a contour which corresponds to one-half of the contour of said working face section in a view on said other end of said block.

2. A tool as set forth in claim 1, in which said working face section comprises a planar central portion, which is parallel to the longitudinal side face which is opposite to said one longitudinal side face, two curved transitional portions which tangentially adjoin said central portion, and two sloping planar end portions respectively extending toward said two longitudinal side faces.

3. In a swaging machine which comprises four hammers, which are spaced 90° apart about an axis along which a work-piece is movable, and which hammers extend radially to said axis, the provision of

5 four tools, each of which is carried by one of said hammers at one end of the latter and comprises

a block having the general shape of a quadrangular prism which has four longitudinal side faces,

said block having a central web, which forms a narrow section of one of said longitudinal side faces and extends from one end of said block approximately over one-half of the length thereof,

10 said one longitudinal side face having a working face section which is wider than said narrow section and extends from the latter to the opposite end of said block and slopes symmetrically to the two longitudinal side faces which are adjacent to said one longitudinal side face,

said web having two side faces, each of which has in a view

on said one longitudinal side face a contour which corresponds to one-half of the contour of said working face section in a view on said other end of said block, each of said tools being secured to one of said hammers at the longitudinal side face of said tool which is opposite to said one longitudinal side face so that said axis extends in the longitudinal direction of each of said blocks and transversely to said two adjoining side faces of each of said blocks,

15 said four tools being generally aligned transversely to said axis, and

said narrow sections of mutually adjacent blocks extending in mutually opposite directions from said working face sections of the respective blocks.

4. In a swaging machine as set forth in claim 3, in which space adjacent said webs permits adjustment of said tools to different depths of penetration.
